AUTOMATIC PRIMER FOR INTERNAL COMBUSTION ENGINES

John W. Fitz Gerald, Milwaukee, Wis., assignor to
 Briggs & Stratton Corporation, Milwaukee,
 Wis., a corporation of Delaware

Application March 12, 1934, Serial No. 715,134

11 Claims. (Cl. 123—180)

This invention relates to certain new and useful improvements in automatic priming devices for internal combustion engines, and has as an object to provide a priming device operable automatically by the throttle control of the engine.

Another object of this invention is to provide thermostatically actuated means to control the operation of the primer by the throttle actuating means.

And a further object of this invention is to provide a priming device of the character described, which is readily applicable to any internal combustion engine and particularly to automotive vehicle engines.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a side view showing part of the carburetor and the manifolds of an internal combustion engine, and illustrating the application of this invention thereto;

Figure 2 is an enlarged side view of the priming device per se;

Figure 3 is a section view taken through Figure 2 on the plane of the line 3—3;

Figure 4 is a top view of the priming device;

Figure 5 is a side view similar to Figure 2, but illustrating the device in the condition which it assumes under higher temperatures; and

Figure 6 is a longitudinal section view through Figure 5 on the plane of the line 6—6.

Referring now more particularly to the accompanying drawings in which like numerals indicate like parts throughout the several views, the numeral 5 designates the carburetor of an internal combustion engine. A fuel supply line 6 leads to the carburetor and its outlet is connected to the intake manifold 7 through a riser 8. A throttle valve 9 is located in the riser 8, as is customary, to be opened and closed by a

link 10 connected to a lever 11, which is fixed to the shaft of the throttle valve. The intake manifold 7, as is customary, is located adjacent the exhaust manifold 12.

The priming device of this invention is indicated generally by the numeral 13 and is mounted by brackets 14 in the region of the exhaust manifold. A pipe line 15 connects the inlet 16 of the priming device with the fuel supply line 6, and a pipe line 17 connects the outlet 18 of the priming device with the intake manifold 7 under certain conditions, as will be hereinafter described. Communication is thus established directly between the fuel supply line 6 and the intake manifold so that fuel may be drawn directly into the intake manifold.

This direct passage for the fuel embodies an axial bore 19 in the body 20 of the priming device, which is enlarged, as at 19', to provide a valve seat 21, and communicates inwardly of the valve seat 21 with a lateral bore 22 leading to the outlet 18. A valve 23 is mounted to engage the seat 21, and close the fuel passage, as shown in Figure 6.

The valve 23 has a pointed nose 24 which enters the longitudinal bore 19 and one side of the nose is flattened to afford a fine adjustment of the degree of communication between the inlet and outlet to closely meter the volume of fuel permitted to pass to the intake manifold.

A stem 25 extends from the valve 23 out through an enlarged bore 26 communicating with the bore 19' to be slidably extended through a plug 27 closing the outer end of the bore 26. The bore 26 forms a pocket for a compression spring 28, confined between the inner end of the plug and a flange 29 on the valve stem to yieldably urge the valve to its closed position.

The extreme outer end portion of the valve stem is threaded and has a stop nut 30 adjustably secured thereon. The valve is opened against the action of the spring 28 by pushing outwardly on the nut 30 and for this purpose, a lever 31 is provided. The lever is medially pivoted as at 32 from a bracket 33, formed as part of the body of the priming device and overhanging the end of the body adjacent the plug 27 to dispose the lower bifurcated end 34 of the lever for active engagement with the nut 30.

When the valve is closed, the lever 31 in an upright position just engages the inner face of the nut 30 and as the lever is swung about its pivot in a clockwise direction with respect to

Figures 2 and 5, the valve stem will be drawn outwardly to open the valve.

The lever 31 is actuated in this manner upon the opening of the throttle valve. The connection between the lever and the throttle valve comprises a lever 35 pivotally mounted from the body of the priming device as at 36 and a link 37 pivotally attached to the lever 35 as at 38. The outer end of the link 37 has an opening 37' to engage over the upper end of the lever 31 and hook itself in one of a series of grooves 39 on the outer face of the lever 31, so that swinging movement of the lever 35 in a clockwise direction imparts a similar movement to the lever 31.

The outer end portion of the lever 35 has a plurality of holes 40, one of which receives a pin 41 which connects the link 10, and a control rod 42 to the lever 35. The control rod 42 leads to the accelerator (not shown) or any other suitable controlling means through which the position of the throttle is regulated.

Hence, it will be seen that whenever the rod 42 is pulled to the right with respect to Figure 1, the throttle valve 9 will be opened and concomitantly therewith, the valve 23 controlling the admission of fuel directly from the supply line to the intake manifold will be opened.

Inasmuch as the admission of priming fuel is desirable only during the starting cycle of the engine or whenever the engine is cold, thermostatically controlled means now about to be described, are provided for controlling the degree of opening of the valve 23, and also disrupting entirely the connection between the throttle control and the priming device when a predetermined temperature has been reached.

To this end, a hairpin shaped bi-metallic strip 44 is secured to the body 20, as at 45. The free end 46 of this bi-metallic strip bears against the underside of the link 37, and the disposition of the metals forming the strip is such that upon a temperature rise thereat, which is obtained by its proximity to the exhaust manifold, the link 37 will be gradually lifted.

As the link 37 is lifted, the leverage between the lever 35 and the lever 31 is decreased so that the valve 23 will be opened less by the operation of the throttle control as the temperature of the engine rises.

When a sufficiently high temperature has been reached, the link 37 will be lifted to its maximum position as defined by a stirrup 47 extending over the top thereof and carried by the body 55 of the priming device. In this maximum position of elevation, the link 37 is entirely disconnected from the lever 31, so that the throttle control functions without in any wise affecting the position of the priming valve, allowing its 60 spring 28 to hold the same closed.

A second thermostatic control in the form of a bi-metallic strip 48 is, however, also provided to determine the degree of closure of the valve 23. This strip 48 is anchored as at 49 to the body 20 and its outer free end carries an adjustable stop screw 40, whose inner end is pointed for engagement with the peripheral inner edge of the nut 30. When the engine is cold, the strip 48 is in the position illustrated in Figure 2, holding its stop screw all the way in to hold the valve open and afford direct communication between the fuel supply line and the intake manifold.

The valve will be held in this open position 75 by the thermostat 48 until the temperature of

the engine has risen sufficiently to move the strip outwardly to carry its stop 50 out of the path of the nut 30. Thereafter, the valve will close under the action of its spring unless the temperature of the engine has not risen sufficiently to disengage the link 37 from the lever 31.

Consequently, during the initial starting of the engine when the engine is cold, the priming valve is continuously held open regardless of the action of the throttle control and after a predetermined temperature has been reached, the priming valve opens and closes in accordance with the opening and closing of the throttle valve until a second predetermined temperature is reached at which the priming valve is allowed to close completely until such conditions again prevail at which a supply of priming fuel is necessary.

From the foregoing description taken in connection with the accompanying drawings, it will be readily apparent to those skilled in the art, that this invention affords a simple priming device for internal combustion engines, which is operable jointly by a thermostatic control and the throttle control, and that the device may be readily applied to any of the conventional automotive vehicle engines.

What I claim as my invention is:

1. An automatic priming device for internal combustion engines having a throttle valve and a control for the throttle valve, a priming valve to control the admission of fuel to the engine, means to yieldably urge said priming valve closed, and a connection between the throttle control and the priming valve to open the priming valve upon actuation of the throttle control.

2. An automatic priming device for internal combustion engines having a throttle valve and a control for the throttle valve, a priming valve to control the admission of fuel to the engine, means to yieldably urge said priming valve closed, a connection between the throttle control and the priming valve to open the priming valve upon actuation of the throttle control, and temperature actuated means to control the actuation of the priming valve by the throttle control.

3. In an automatic primer for internal combustion engines having a throttle valve and a control therefor, a priming valve to control the admission of fuel to the engine biased to closed position, a connection between the priming valve and the throttle control to open the priming valve simultaneously with the opening of the throttle valve, and temperature actuated means to determine the degree of opening of the priming valve by said throttle control.

4. In an automatic primer for internal combustion engines having a throttle valve and a control therefor, a priming valve to control the admission of fuel to the engine biased to closed position, a connection between the priming valve and the throttle control to open the priming valve simultaneously with the opening of the throttle valve, and temperature actuated means to disrupt the connection between the priming valve and the throttle control upon the attainment of a predetermined ambient temperature, so that after such temperature is reached, the throttle control is ineffective to open the priming valve.

5. An automatic priming device for internal combustion engines having a throttle valve and a control therefor, a priming valve to control the admission of fuel to the engine biased to closed position, and a connection between said

priming valve and the throttle control whereby actuation of the throttle control to open the throttle valve also opens the priming valve, said connection including a pivoted lever and a link engageable with the lever at different distances from its pivotal axis, and temperature actuated means to vary the point of connection between the link and the lever and thereby control the degree of opening of the priming valve by the 10 throttle control.

6. In an automatic priming device for internal combustion engines having a throttle valve and a control therefor, a valve to control the admission of fuel to the engine, a spring to yieldably hold the valve closed, a connection between the priming valve and the throttle control to open the priming valve as the throttle valve is opened, said connection comprising, a pivoted lever, a link detachably connected with said 15 lever and a thermostat to move the link to a position incapable of connection with said lever upon a temperature rise at a selected region of the engine whereby the priming valve is opened in conjunction with opening of the throttle valve 20 only until predetermined temperature conditions in the engine have been attained.

7. In an automatic priming device for internal combustion engines having a throttle valve and a control therefor, a priming valve to control the admission of fuel to the engine, a connection between the priming valve and the throttle control comprising, a pivotally mounted lever, a second lever pivotally mounted and permanently connected with the throttle control to 30 move directly therewith, a link to connect said levers, and temperature actuated means to disconnect the link from one of said levers upon a predetermined temperature rise in a selected region of the engine, whereby the priming valve 35 is opened in conjunction with the opening of the throttle valve only until such predetermined temperature has been attained.

8. In an automatic priming device for internal combustion engines having a throttle valve and a control therefor, a priming valve to control the admission of fuel to the engine, a connection between the priming valve and the throttle control comprising, a pivotally mounted lever, a second lever pivotally mounted and permanently connected with the throttle control to 40 move directly therewith, a link pivotally connected to one of said levers and having a detachable connection with the other lever at different distances from the pivotal axis of said other 45 lever so as to vary the leverage of the connection

between said levers, and temperature actuated means to move said link about its pivotal attachment to the first designated lever and vary the position of its connection to the second designated lever, whereby the degree of opening 5 of the priming valve by the throttle control is regulated in accordance with temperature variations in a selected region of the engine.

9. An automatic priming device for internal combustion engines comprising, a valve to control the admission of fuel to the engine, a spring to yieldably urge the valve closed, temperature actuated means operable to open the valve against the action of the spring and to hold the valve open until a predetermined high temperature has been reached, a manually operable member, and means to connect said manually operable member with the valve to open the valve against the action of its spring whereby the valve may be opened after the temperature 20 actuated means has permitted the same to be closed by its spring.

10. An automatic priming device for internal combustion engines comprising, a valve to control the admission of fuel to the engine, a spring to yieldably urge the valve closed, temperature actuated means operable to open the valve against the action of the spring and to hold the valve open until a predetermined high temperature has been reached, a manually operable member, means to connect said manually operable member with the valve to open the valve against the action of its spring whereby the valve may be opened after the temperature 30 actuated means has permitted the same to be 35 closed by its spring, and a second temperature actuated means to disconnect the valve from the manual control upon the attainment of a second predetermined higher temperature.

11. In an automatic priming device for internal combustion engines having a throttle valve and a control therefor, a valve to control the admission of fuel to the engine, a spring to close the valve, temperature actuated means to open and hold the valve open against the action of the spring until a predetermined temperature rise has been obtained, a connection between the valve and the throttle control to open the valve, and a second temperature actuated means to render said connection between the valve and the throttle control ineffective upon the attainment of a second predetermined higher 40 temperature.

JOHN W. FITZ GERALD. 55
